UNITED STATES PATENT OFFICE

116,875

DESIGN FOR A SCARF OR SIMILAR ARTICLE

Benjamin F. Goodman, New York, N. Y.

Application July 13, 1939, Serial No. 85,989

Term of patent 3½ years

To all whom it may concern:

Be it known that I, Benjamin F. Goodman, a citizen of the United States of America, residing in the city of New York, county of New York, and State of New York, have invented a new, original, and ornamental Design for a Scarf or Similar Article, of which the following is a specification, reference being had to the accompanying drawing, forming part thereof.

Fig. 1 is a plan view of a scarf or similar article showing my new design.

Fig. 2 is an enlarged fragmentary view showing one-half of the scarf shown in Fig. 1.

I claim:

The ornamental design for a scarf or similar article, substantially as shown and described.

BENJAMIN F. GOODMAN.
